UNITED STATES PATENT OFFICE.

EMIL STOHN, OF JERSEY CITY, NEW JERSEY.

DESIGN FOR FABRIC.

SPECIFICATION forming part of Design No. 28,249, dated February 1, 1898.

Application filed December 22, 1897. Serial No. 663,104. Term of patent 3 $\frac{1}{2}$ years.

To all whom it may concern:

Be it known that I, EMIL STOHN, a citizen of the United States, residing at Jersey City, in the county of Hudson, State of New Jersey, have invented and produced a new and original Design for Fabric, of which the following is a specification, reference being had to the accompanying drawings, forming part thereof.

10 The leading feature of my design for a fabric is a spray whose leaves droop from the stem thereof.

Figure 1 represents a face view of a piece of fabric embodying my design. Fig. 2 represents a section thereof on line $x\ x$, Fig. 1.

15 In the drawings, A designates a piece of

fabric, on the face of which are sprays B, whose leaves C droop from the stem D, the latter being curved. The sprays of one row alternate with those of the adjacent row, and 20 the leaves of the different rows turn, respectively, in opposite directions.

Having described my invention, what I claim as new, and desire to secure by Letters Patent, is—

25 The design for a fabric substantially as shown and described.

EMIL STOHN.
